(57) **CLAIM**

The ornamental design for a mint container, as shown and described.

DESCRIPTION

FIG. 1 is a perspective view of the inventive mint container; FIG. 2 is a top plan view of the mint container;

FIG. 3 is a side elevational view of the mint container of FIG. 1, with the opposite side elevational view being a mirror image thereof;

FIG. 4 is a bottom plan view of the mint container of FIG. 1;

FIG. 5 is a first end elevational view of the mint container; FIG. 6 is the other end elevational view of the mint container; and,

FIG. 7 is a perspective view of the mint container with the top in an open position.
